14 Claims. (Cl. 230—143)

1

The present invention relates to positive displacement rotary devices for the compression or expansion of elastic fluids, and has particular reference to such devices of the type in which working spaces or chambers of variable volume are formed between cooperating helically grooved rotors. Still more particularly the invention relates to such devices in which the working spaces are defined in part by a casing end wall at the high pressure end of the rotors and which may also be defined in part by such a wall at the low pressure end of the rotors. An example of such device is disclosed in U. S. Patent No. 2,174,522, granted to Alf Lysholm.

It is the general object of the present invention to improve the efficiency of such devices by new and improved porting arrangements operative to reduce the dynamic losses, as hereinafter explained, and since the principles of the invention are applicable in the same way to produce improved performance whether the device is operated as a fluid compressor or as a fluid actuated motor, it will be sufficient for the purpose of explaining the invention to describe it as applied to a device operated as a compressor. The manner in which the general and more detailed objects of the invention are secured, together with the advantages to be derived from its use, will appear more fully as the following portion of this specification, which is to be read in conjunction with the accompanying drawings, proceeds.

In the drawings:

Fig. 1 is a top plan view of a device embodying the invention;

Fig. 2 is a side elevation of the device shown in Fig. 1;

Fig. 3 is a view taken on line 3—3 of Fig. 1;

Fig. 4 is a view taken on line 4—4 of Fig. 1;

Fig. 5 is a view of the top half of the casing, viewed from below and with the rotors removed;

Fig. 6 is a view of the bottom half of the casing viewed from above and with the rotors removed; and

Fig. 7 is a view showing the rotors.

One of the basic characteristics of devices of the kind to which this invention relates is that the intermeshing rotors, the grooves of which provide the working chambers, are of the type in which one rotor, usually referred to as the male rotor, is provided with lands and grooves

2

the major portions of which, and preferably substantially in their entirety, lie outside of the pitch circle, or in other words in the addendum region of the rotor, while on the other hand the cooperating or female rotor has the major portions or substantially all of its lands and grooves located within the pitch circle, in the dedendum region of the rotor.

Such rotors, as will hereinafter appear, provide flow characteristics quite different from those produced by rotors of the twin or Roots type, and in brief it may be stated that in one aspect of the invention I accomplish the desired objects by providing passages for flow of fluid to or from the working chambers through passages so located and arranged that the flow is lateral and generally tangential with reference to the addendum region of the male rotor. In another aspect, I obtain improved results by providing the fluid passages communicating with the parts with throats located as near as conveniently possible to the ports, such throats providing the minimum cross-sectional area of the passages and having areas so related to the volumetric capacity of the rotor grooves that the velocity of fluid flow through the throats approximates the velocity of travel of the addendum region of the male rotor. From such throats, on the side away from the port with which the throat communicates, the fluid passages are preferably made of nozzle-like or diffuser form, for most efficient conversion of the kinetic energy of the fluid to static pressure energy, or vice-versa, as the case may be. In still another aspect, I employ port contour designed to preserve, as far as possible, uniformity of speed of fluid between the grooves of the male rotor and the throat portions of the communicating passages, thereby reducing or substantially eliminating dynamic losses occasioned by local acceleration or deceleration of the fluid.

In order to illustrate the application of the principles of the invention to a practical device I have shown in the accompanying drawings one example, which will be described in its operation as a compressor, but it will be understood that the specific design shown is illustrative only and not limiting as to the scope of the invention, some of the features of which may be used to the exclusion of others, and which is defined by the appended claims.

Referring now to the drawings, the compressor comprises a casing indicated generally at 10 and in the embodiment illustrated consisting of a middle section 12, and inlet and outlet end sections 14 and 16 respectively. The middle section is formed with two parallel cylindrical and intersecting bores the outlines of which are shown by the lines 18 and 20 in Figs. 3 and 4. The inlet and outlet sections have plane end walls 22 and 24 forming end closures and cooperating with the side or radial walls in the middle section to form intersecting barrels for the reception of the helically grooved rotors indicated generally at 26 and 28 (Fig. 7), 26 being the male rotor and 28 the female. In the example shown the rotors each have four lands and grooves, and the tooth or land profile shown is that disclosed in the aforesaid Lysholm patent. The invention is, however, independent of specific tooth profile and the number of grooves per rotor, which may be the same or different in two intermeshing rotors.

Rotors 26 and 28 are mounted for rotation in the respective barrels by means of suitable bearings in the end sections of the casing, in known manner, and are maintained in properly spaced rotational relation by the usual timing gears located in the housing section 16. Such construction is conventional and need not be illustrated in detail for an understanding of this invention.

As will be seen particularly from Figs. 1 to 3, the casing structure provides a laterally extending inlet or induction passage 30 having walls converging in the direction of gas flow to give smooth contraction of cross-sectional area to the throat 32. In the embodiment illustrated this passage is formed partly in the end section and partly in the middle section of the casing, and communicates with an inlet port having portions located in the side and one end wall of the barrels housing the rotors. The configuration of the end wall portion of the port is shown by the line *a*—*b*—*c*—*d*—*e*—*f*—*g*—*h* in Fig. 3, and the outline of the portion of the port in the side wall is shown by the line *k*—*l*—*m*—*n*—*o* in Fig. 5, the port thus providing both radial and axial communication with the working chambers formed by the rotor grooves.

At the outlet or discharge end the construction is generally similar to that just described, providing an outlet passage 34 of smoothly increasing or diffusorlike section leading from the throat 36 which communicates with a combined outlet port having a portion in the outlet end wall as shown by line *a'*—*b'*—*c'*—*e'*—*d'*—*f'*—*g'*—*h'*—*i'* in Fig. 4 and a portion in the side wall shown by line *k'*—*l'*—*m*—*n*—*o* in Fig. 6. This port, like the inlet port provides for both axial and radial communication with the working chambers.

Ports providing combined radial-axial communication with the working chambers are not new per se, and have been herein illustrated since in most instances they are the most desirable form, but for reasons hereinafter dealt with it may be desirable or necessary to provide all or substantially all communication through an end wall port or through a side wall port. Insofar as the nature of the passage leading to the port is concerned, the present invention applies equally to radial, axial and combined forms of ports, different types of which may be used for the inlet and outlet of the same device.

The general principle of operation of the described device is well known and need not be given here in detail, but it may be said that the

cycle of operation is divided into four phases, (1) the inlet or induction phase during which the rotor grooves are filled through the inlet port as the grooves pass the port, (2) the transport phase during which the fluid is carried at constant volume peripherally after the grooves have passed out of communication with the inlet port and before they communicate with the outlet port, (3) the compression phase, during which the volumes of the grooves are decreased by the action of cooperating grooves and lands which in effect travel axially to reduce the lengths of the chambers before the grooves come into communication with the outlet port and (4) the discharge phase, which is in effect a second transport phase, and in which the compressed fluid is transported from the working chambers to the discharge passage through the outlet port as the chambers are reduced to final zero volume by the action of the intermeshing grooves and lands. It is with the first and last of the above described phases that this invention is particularly concerned in one of its aspects, and for purposes of explanation, the application of certain principles of the invention to the discharge phase of the operation will first be considered. In the operation of the device as a compressor, the rotors turn in the directions indicated by arrows 38 and 40 in Fig. 4 and the trapped volumes of fluid, being compressed in the grooves 42 of the male rotor and grooves 44 of the female rotor, are traveling at the respective peripheral velocities of the different grooves. In this connection it is highly important to note that because of the fundamental characteristic of this type of device, i. e., that the grooves of the male rotor are in the addendum region and the grooves in the female rotor are in the dedendum region, the peripheral speed of the male grooves is always very considerably greater than that of the female grooves. This holds true regardless of the relative number of grooves and the relative diameters of the two rotors. In any design such as that illustrated, wherein the two rotors have the same number of grooves, their rotative speeds will be the same and the female rotor will be of smaller diameter than the male. With other combinations of groove numbers in the respective rotors the female may have more grooves than the male and may be of larger diameter, but in such case the female rotor will turn at a lower number of revolutions than the male, so that in all cases where male and female rotors are employed the peripheral speed of the female grooves will be less than that of the male grooves, since one set is traveling within the pitch circle and the other set is traveling outside the pitch circle. Also it is to be noted that the volumes of the male grooves are in most cases substantially greater than the volumes of the female grooves. Devices of the kind under consideration operate at relatively high speeds, peripheral speeds for the tips or crests of the male rotor lands in the range of from 100 to 200 meters per second or even higher being desirable, maximum speed in many cases being limited only by practical considerations such as the life of high speed bearings and the like. Since the kinetic energy represented by the inertia of a moving body varies as the square of its velocity, it will readily be seen that in a device of the kind described the kinetic energy of the masses of gas in the male grooves is much greater than that in the female grooves since ordinarily the masses are greater and in all cases the peripheral speed is materi-

ally greater. Calculations show that for many of the designs now in practical use, the kinetic energy of the fluid in the male grooves may be as much as from six to ten times that of the fluid in the female grooves.

The magnitude of this difference has apparently not heretofore been fully appreciated, nor has its effect on losses incurred during the discharge phase of the cycle been fully understood.

I have found from actual test experience that appreciable improvement in efficiency is obtained if the discharge passage is designed particularly with reference to the male rotor grooves and so located and arranged with reference thereto that the fluid discharged from the male grooves travels therefrom laterally in generally tangential direction, without abrupt change in the direction and with minimum change in velocity, to the throat of the discharge passage, from which point its kinetic energy may be transformed efficiently to static energy in a diffusor like channel. This involves discharge generally laterally from the groove and the manner in which this is accomplished by the present invention may be seen by reference particularly to Figs. 4 and 6. As will be seen from Fig. 4, the portion of the discharge channel leading from the port to the throat, the center line or axis of which is indicated by the line 46, is laterally directed toward the side of the casing housing the female rotor and inclined away from the plane 48 common to the rotor axes so that this part of the passage is tangential to the addendum region of the male rotor. If other design conditions permit, it is desirable that the axis of the passage be tangential to a circle lying slightly outside of the center of gravity of the groove, but variation from this is not critical. In Fig. 6, the direction of rotation of the male rotor is shown by arrow 38 and the crests of two adjacent lands are shown at 50. As will be evident, the flow of fluid from the groove limited by these crests will be lateral in the direction of arrow 52 and tangentially under the port edge $m'-n'-o'$ to the throat region located at the section indicated at 38. The direction of travel of the female rotor is shown by arrow 40 and at 54 the lines of the crests of the female lands are shown. From these and from Fig. 4 it will be seen that the arrangement of the passage requires an abrupt change in direction of the fluid flowing from the female grooves to the throat, but I have found that any loss incurred because of this factor is far outweighed by the improvement gained in the flow from the male grooves, as compared with prior arrangements in which the outflow from the two sets of grooves is more symmetrical with reference to the central axial plane normal to the plane of the rotor axes, and that the overall efficiency is appreciably increased.

In devices of the character under consideration, the compression ratio obtained in the working chambers may be varied by altering the outlet port. By making the port smaller, so that the rotors must turn through a greater angle, after compression starts, before communication with the discharge is opened, the pressure ratio is increased. This involves shortening the axial extent of the side wall port and the peripheral extent of the end wall port as pressure ratio is increased, and for relatively high pressure ratios the axial length of the side wall port may become so short that the end wall port area may be predominant and in some cases the side wall portion of the port may be omitted entirely. On

the other hand, for relatively low compression ratios, such as are used for scavenging or supercharging internal combustion engines, the side wall portion of the port may be quite long axially, so that axial discharge from the chambers becomes less important and in some instances the end wall portion of the port may be entirely eliminated. In all cases, however, the outflow from the male grooves is lateral and depending upon the relative proportions of the end and side wall portions of the ports, or upon the elimination of one or the other of such portions, the inclination of the angle of the discharge passage with respect to the transverse plane normal to the rotor axes will vary. In the compressor illustrated, the proportions of the ports are suitable for a "built in" compression ratio of approximately two to one. For a compressor of lower ratio, with a longer side wall port, the discharge passage may advantageously be designed so that the general direction of outflow from the male grooves, indicated by arrow 52, is more nearly or even normal to the rotor axes, while for a higher ratio and consequently shorter side wall port, the direction of such outflow, laterally, may advantageously be at a lesser angle with respect to an axial plane than is indicated by arrow 52. Thus, as herein employed, the term lateral is not intended to be limited to, but may include, a direction at right angles to the rotor axes. Also, as seen in Fig. 4, the angle of inclination of the passage, as indicated by line 46, with respect to the plane 48, may vary widely depending upon the relative diameters of the male and female rotors. Thus if the female rotor has a diameter relative to the male rotor greater than that shown, owing to a different relation in numbers of grooves in the two rotors, the included angle between 46 and 48 will be greater than that shown, but in all cases, insofar as this aspect of the invention is concerned, the passage will be inclined toward the side of the casing housing the female rotor and arranged so that the flow from the male rotor grooves will be substantially tangential thereto from the throat of the outlet passage.

The same general principles apply to the inlet porting and passage arrangements, since losses at this end of the device may be materially lessened through smooth acceleration of the rate of flow of the relatively static fluid to the throat of the inlet passage and from there tangentially and without abrupt change in direction or velocity into the grooves of the male rotor which are traveling at high peripheral velocity. Also, as in the case of the outlet passage, the specific design will dictate the specific angle of the passage with reference to the planes parallel with and at right angles to the rotor axes.

Taking the foregoing into account, it will be seen that whether the passage is an inlet or a discharge passage, it is characterized by an arrangement providing a lateral and generally tangential direction of flow from the male rotor grooves toward the side of the casing housing the female rotor, or vice versa, with the lateral flow also having in most cases, but not necessarily so, a flow angular with respect to a plane normal to the rotor axes.

I have also discovered that improvement in efficiency is obtained by so proportioning the passages communicating with the working chambers that the velocity of flow through the throats thereof approaches approximately the peripheral velocity of the average diameter of the male rotor grooves, and as herein employed the

term approximates is intended to cover the range of values of from approximately 80% to approximately 100% of such rotor groove speed. In each individual case, the dimensioning of the throat to secure the designed velocity of flow is readily accomplished, since the volumetric capacity of the grooves is a determinable quantity. With this known, it is then a matter of simple calculation to so relate the area of the throat to the volume delivered from or inducted to the 10 grooves that the desired relation between the peripheral velocity of the male grooves and the velocity of flow through the throat is obtained.

While the arrangements and dimensions of 15 passages to and from the working chambers just described contribute substantially to improved performance, the port configuration is also important in reducing dynamic losses between the working chambers and the throats of the passages. This is particularly true with reference to 20 side wall or radial port configuration. In previous constructions, the edges of the radial port have been made angular throughout their length, in substantial conformity with the angularity of the lands of the rotors, so that the grooves of the 25 rotors would come into registry with the port substantially simultaneously along the entire length of both sides of the port. Such porting configuration is illustrated in the Lysholm Patent No. 2,174,522 previously mentioned and also in Lysholm Patent No. 2,243,874. These arrangements have been proposed, however, primarily with the thought in mind of securing quick opening of the port and elimination of loss through "wire drawing." I have found, however, that improvement in performance is obtained if a narrower and more elongated form of port is employed, which operates to maintain more uniform 30 velocity of flow from the rotor grooves to the throat of the outlet passage (or vice versa) than the generally triangular form of port heretofore employed. In order to illustrate what I believe to be the reason for this I have shown in Fig. 7, the 35 discharge ends of two cooperating rotors 26 and 28 with the outline of the radial outlet port shown thereon by the dotted line $k'-l'-m'-n'-o'$. The direction of rotation of the rotors is shown by arrows 38 and 40. As the rotors revolve, the crest or apex 50 of one male rotor land passes underneath the leading edge 54 of the crest of a co-operating female land to enter the female grooves 56, which is already in communication with the port, as is also the male groove 58 ahead of the 40 crest 50. The point of intersection of these two edges advances axially toward the discharge end wall 24 as the rotors revolve and the fluid displaced from between the approaching faces of the lands tends to flow axially as indicated by arrow 60. The same character of flow is produced by the intersection of the next succeeding intersecting edges 50a and 54a as indicated by arrow 60a. At the outlet end of the rotor grooves, however, the direction of movement of the fluid is at right angles to the rotor axes, as indicated by 45 arrows 62 and 64, this direction of flow being imposed by the end wall 24 until communication with an axial end wall port is established. As a result, the directions of the average flow may approximate those of arrows 66 and 68, and for this average flow it is desirable to maintain as 50 nearly as possible a uniform velocity of travel to and through the port to the outlet throat. To this end the present port outline contributes by covering the portions of the grooves adjacent to the outlet end of the rotors, after they have 55

first come into communication with an outlet port. From Fig. 7 it will be seen that with the port configuration provided, the male rotor grooves are covered by the side wall over the area $k'-l'-x$, which would be open port area if the previously used triangular form of port were employed, while the female grooves are covered by the wall area $m'-n'-o'-y$, which would otherwise be open port area. The portion of the port edge $l'-m'$ is preferably diagonal as shown, on a line approximating the helix angle of the male rotor lands, so that initial opening of the port to a substantial area will be effected by a comparatively few degrees of rotor movement.

The position of the sealing line between intermeshing pairs of lands and grooves is indicated by line Z and as will be seen from Fig. 7, this creates a pocket extending axially behind the point of intersection of the crests of the lands. This pocket advances toward the discharge end as the rotors revolve and finally runs out to zero volume. In order to facilitate discharge from this pocket, the port edge is advantageously made diagonal along the line $n'-o'$.

While in the example shown the side edges of the port are parallel with the rotor axes, the specific outline may be changed without departing from this phase of the invention, the principal criterion being that the port outline be such as to maintain a velocity of flow through the port approximating that of the fluid in the grooves delivering to it. Generally speaking, this is accomplished by shaping the side wall port so that the grooves first open into the port at a place axially spaced from the ends of the rotors and thereafter progressively register with the port in the direction toward the rotor ends.

In the compressor illustrated, the peripheral extent of the end wall portions of the ports and the axial length of the side wall portions of the ports are so related to the helix angle of the grooves that both portions of each port register simultaneously with any given groove. This however is not essential and depending upon specific factors of design such as the compression ratio desired, speed of operation, the number of lands and grooves in the different rotors, helix angles, etc., this relation of the time of opening or closing of the different parts of a combined radial-axial port may readily be changed by altering the relation between the length of the radial part and the peripheral extent of the axial part.

While as has previously been noted, the device has been described in its action as a compressor, it will readily be apparent that the same principles apply to its action as a motor, in which case the rotors are revolved in directions opposite those shown herein and the port at the high pressure end becomes the inlet rather than the outlet port, while the low pressure port becomes the outlet port. In such case the same flow factors apply in reducing dynamic losses both with respect to the admission of high pressure motive fluid to the working chambers and the exhausting of the expanded fluid from the device.

Obviously the invention is applicable to many different structural designs and its scope is therefore to be considered as limited only by the terms of the appended claims.

I claim:

1. In a rotary device, a casing structure providing two parallel intersecting barrels and having inlet and outlet ports communicating with said barrels, a male rotor having helical lands and grooves the major portions of which lie outside

the pitch circle of the rotor and mounted for rotation in a first one of said barrels, a female rotor having helical lands and grooves the major portions of which lie within the pitch circle of the rotor and mounted in a second one of said barrels and intermeshing with said male rotor, a fluid conducting passage in said casing structure communicating with one of said ports and extending therefrom in a laterally inclined direction toward the side of said casing structure providing said second barrel and away from the plane common to the axes of said rotors.

2. In a rotary device, a casing structure providing two parallel intersecting barrels and having inlet and outlet ports communicating with said barrels, a male rotor having helical lands and grooves the major portions of which lie outside the pitch circle of the rotor and mounted for rotation in a first one of said barrels, a female rotor having helical lands and grooves the major portions of which lie within the pitch circle of the rotor and mounted for rotation in a second one of said barrels and intermeshing with said male rotor, a fluid conducting passage in said casing structure communicating with one of said ports and extending therefrom in a laterally inclined direction toward the side of said casing structure providing said second barrel and away from the plane common to the axes of said rotors, said passage also being inclined longitudinally of the rotors in a direction away from the longitudinally central portions thereof.

3. In a rotary device, a casing structure providing two parallel intersecting barrels, a male rotor having helical lands and grooves the major portions of which lie outside the pitch circle of the rotor and mounted for rotation in a first one of said barrels, a female rotor having helical lands and grooves the major portions of which lie within the pitch circle of the rotor and mounted in a second one of said barrels and intermeshing with said male rotor, inlet and outlet ports in said casing structure communicating respectively with the opposite end portions of said barrels on respectively different sides of the plane common to the rotor axes, and fluid conducting passages communicating respectively with said ports and extending therefrom laterally toward the side of said casing structure providing said second barrel and in oppositely inclined directions away from said plane.

4. In a rotary device, a casing structure providing two parallel intersecting barrels, a male rotor having helical lands and grooves the major portions of which lie outside the pitch circle of the rotor and mounted for rotation in a first one of said barrels, a female rotor having helical lands and grooves the major portions of which lie within the pitch circle of the rotor and mounted in a second one of said barrels and intermeshing with said male rotor, inlet and outlet ports in said casing structure communicating respectively with the opposite end portions of said barrels on respectively different sides of the plane common to the rotor axes, and fluid conducting passages communicating respectively with said ports and extending therefrom laterally toward the side of said casing structure providing said second barrel and in oppositely inclined directions away from said plane, at least one of said passages also being inclined longitudinally of the rotors in a direction away from the longitudinally central portions thereof.

5. In a rotary device, a casing structure providing two parallel intersecting barrels, a male rotor having helical lands and grooves the major

portions of which lie outside the pitch circle of the rotor and mounted for rotation in a first one of said barrels, a female rotor having helical lands and grooves the major portions of which lie within the pitch circle of the rotor and mounted in a second one of said barrels and intermeshing with said male rotor, inlet and outlet ports in said casing structure communicating respectively with the opposite end portions of said barrels on respectively different sides of the plane common to the rotor axes, and fluid conducting passages communicating respectively with said ports and extending therefrom laterally toward the side of said casing structure providing said second barrel and in oppositely inclined directions away from said plane, said passages also being oppositely inclined longitudinally with respect to each other and away from the longitudinally central portions of said rotors.

20 6. In a rotary device, a casing structure providing two parallel intersecting barrels and having inlet and outlet ports communicating with said barrels, a male rotor having helical lands and grooves the major portions of which lie outside the pitch circle of the rotor and mounted for rotation in a first one of said barrels, a female rotor having helical lands and grooves the major portions of which lie within the pitch circle of the rotor and mounted in a second one of said barrels and intermeshing with said male rotor, and a fluid conducting passage in said casing structure communicating with one of said ports, said passage having a throat adjacent to the port with which it communicates and a portion of expanding cross sectional area leading from said throat, the portion of said passage between said port and said throat extending laterally in tangential direction from the addendum region of the male rotor toward the side of the casing structure providing said second barrel.

7. In a rotary device, a casing structure providing two parallel intersecting barrels and having inlet and outlet ports communicating with said barrels, a male rotor having helical lands and grooves the major portions of which lie outside the pitch circle of the rotor and mounted for rotation in a first one of said barrels, a female rotor having helical lands and grooves the major portions of which lie within the pitch circle of the rotor and mounted in a second one of said barrels and intermeshing with said male rotor, and a fluid conducting passage in said casing structure communicating with one of said ports, said passage having a throat adjacent to the port with which it communicates providing the minimum cross sectional area of the passage and the area of said throat being related to the displacement of the grooves in said rotors to provide a velocity of fluid flow through said throat approximating the average peripheral velocity of the grooves in the male rotor.

8. A device as set forth in claim 7 in which said passage is formed to provide a nozzle like portion of gradually increasing cross sectional area leading from said throat.

9. In a rotary device, a casing structure providing two parallel intersecting barrels and having inlet and outlet ports communicating with said barrels, a male rotor having helical lands and grooves the major portions of which lie outside the pitch circle of the rotor and mounted for rotation in a first one of said barrels, a female rotor having helical lands and grooves the major portions of which lie within the pitch circle of the rotor and mounted in a second one

11

of said barrels and intermeshing with said male rotor, and a fluid conducting passage in said casing structure communicating with one of said ports, the port with which said passage communicates providing an opening in the radial walls of said barrels extending longitudinally from one end thereof and of greater length than width and said passage communicating laterally with said opening from the side of the casing structure providing said second barrel.

10. A device as set forth in claim 9 in which the side edges of the port extend in generally longitudinal direction.

11. A device as set forth in claim 9 in which the side edges of the port extend in generally longitudinal direction and are connected by an end edge at least the major portion of which extends diagonally at approximately the same angle as the helix angle of the lands of the male rotor.

12. In a rotary device, a casing structure including side walls and an end wall defining two parallel intersecting barrels and having inlet and outlet ports communicating with said barrels, a male rotor in a first of said barrels, a female rotor in a second of said barrels, said rotors having intermeshing helical lands and grooves cooperating with each other and with the casing side and end walls to form working chambers for fluid varying in volume as the rotors turn, at least one of said ports in said casing structure having portions in both said side and end walls, and a fluid conducting passage communicating with one

of said ports and leading therefrom in a direction providing a more direct line of flow of fluid between the grooves of the male rotor and said passage than between the grooves of the female rotor and the passage.

13. A device as set forth in claim 12 in which the direction of said passage is diagonal with respect to the plane common to the axes of said rotors.

14. A device as set forth in claim 12 in which the direction of said passage is diagonal with respect to both the plane common to the axes of said rotors and a plane normal to said axes.
